US00D811748S

(12) United States Design Patent (10) Patent No.: US D811,748 S
(45) Date of Patent: * Mar. 6, 2018

(54) TOOTHBRUSH

(71) Applicant: The Gillette Company LLC, Boston, MA (US)

(72) Inventors: Franziska Schmid, Frankfurt/Main (DE); Tilmann Winkler, Kronberg (DE)

(73) Assignee: THE GILLETTE COMPANY LLC, Boston, MA (US)

() Term: 15 Years

(21) Appl. No.: 29/556,170

(22) Filed: Feb. 29, 2016

Related U.S. Application Data

(62) Division of application No. 29/501,810, filed on Sep. 9, 2014, now Pat. No. Des. 753,401.

(57) CLAIM

The ornamental design for a toothbrush, as shown and described above.

DESCRIPTION

FIG. 1 is a perspective view of a toothbrush showing our new design;

FIG. 2 is a front view thereof;

FIG. 3 is a right side view thereof;

FIG. 4 is a rear view thereof;

FIG. 5 is a left side view thereof;

FIG. 6 is a top plan view thereof; and,

FIG. 7 is a bottom view thereof.

The broken lines are shown for the purpose of illustrating parts of the toothbrush that form no part of the claimed design.
